ABSTRACT OF THE DISCLOSURE

A drilled stack of sheets is bound by plastic that elements are pre-formed into multi-leg devices by means of a rotating die which sets the heat softened element into a finished shape. These are then inserted into the drilled openings by a spreading mechanism.

BACKGROUND OF THE INVENTION

Field of the invention

This invention relates generally to sheet binding and more particularly is directed towards new and improved sheet binding devices, apparatus for forming the binding elements and finally apparatus for inserting the binding elements in the drilled stack.

Description of the prior art

In U.S. patents numbered 2,377,340, 2,850,927 and 3,073,355 there are disclosed various portions of a sheet binding apparatus adapted to form binding elements from wire, drilling a pile of sheets to be bound, and inserting the binders through the drilled holes in the sheets. The apparatus discloses in these patents at the time represented a substantial advance in the art of sheet binding insofar as it is capable of high productivity as well as producing a bound volume of improved quality. The present invention has for one of its objects providing improvements in the sheet binding apparatus disclosed in the foregoing patents and specifically for providing sheet binding mechanisms and sheet binding elements capable of producing bound volumes such as notebooks, check books, paper back books, calendars, loose-leaves or the like at a much higher rate of productivity and producing bound volumes of superior characteristics and of uniform quality.

SUMMARY OF THE INVENTION

This invention features novel binding elements for binding a drilled stack of sheets. The elements are pre-formed one-piece multi-looped devices of plastic. The plastic binding elements are formed by an apparatus which includes a ramp along which individual elements are fed past a heat source to soften the elements prior to delivery to a rotary die mechanism which forms and sets the elements into the desired loops.

BRIEF DESCRIPTION OF THE DRAWINGS

FIG. 1 is a view in side elevation, somewhat schematic, of an apparatus for forming plastic binding elements according to the invention,

FIG. 2 is a view in perspective of a binding element made by the FIG. 1 apparatus,

FIG. 3 is a top plan view, partly in section of the forming die of FIG. 1,

FIG. 4 is a detail end view of an apparatus for temporarily opening plastic binding elements,

FIG. 5 is a modification thereof.

2

DESCRIPTION OF THE PREFERRED EMBODIMENT

Referring to FIGS. 1, 2 and 3, there is illustrated a binding element of plastic material along with the apparatus for making the same. As shown in FIG. 2 a binding element 120 is formed with an elongated cross-piece 122 from which extends a plurality of substantially closed loops 124 spaced from one another and adapted to be inserted in the drilled openings of a pad of paper. The binding element of FIG. 2 is formed by the mechanism illustrated in FIGS. 1 and 3. The mechanism includes an inclined upper chute 126 for storing a supply of binding elements 120 which at this stage comprises simply the straight cross-piece 122 and a plurality of straight depending legs 128 which are to be formed into the loops shown in FIG. 2. The binding elements are restrained on the chute 126 by means of an indexing wheel 130 which, upon actuation, is adapted to dispense the binding elements one-by-one onto an inclined lower chute 132. Binding elements stored in the upper chute 126 are subjected to a heat source directed through a vent 134, this heat source being at a selected temperature which pre-heats the supply of binding elements indefinitely without damage to them. When the indexing wheel 130 is actuated the leading binding element is dispensed onto the lower chute 132 where it slides down and is temporarily stopped by means of a release mechanism 136. The release mechanism holds the element 120 below a second and higher intensity heat source 138 which raises the individual element to a forming temperature. When the element 120 has reached the proper temperature the release mechanism 136 is actuated permitting the element 120 to slide down to a forming mechanism 140.

This mechanism includes a die 142 comprised of upper and lower blocks 144 and 146 respectively. These blocks are hinged to one another and adapted to be opened and closed automatically on signal by any suitable means such as a solenoid or the like. The blocks are formed with a horizontal cylindrical mandrel 150. The mandrel is formed with a longitudinal groove 152 adapted to receive the cross-piece portion 122 of the binding element. As shown in FIG. 1, the binding element is delivered to the forming mechanism with the cross-piece leading and being picked up by the groove in the mandrel which is shown in its start position in FIG. 1. The cylindrical walls of the die passage are formed with annular grooves 154 positioned and dimensioned to receive the legs of the binding element. When the binding element is fed into the forming mechanism and its cross-piece 122 received in the mandrel groove, the mandrel is rotated as by a motor 156. Rotation of the mandrel serves to draw the binding element into the forming mechanism counterclockwise as viewed in FIG. 1. This will wrap the binding element about the mandrel to form the straight legs into the loops 124. Once the binding element has been wrapped about the mandrel, it is allowed to set long enough for the plastic material to stabilize in its new shape. To this end the upper and lower blocks of the die are provided with a cooling system, the cooling medium being pumped through conduits 156 and 158. When the binding element has fully set, the forming blocks open and a traveling sweep 160 is actuated to slide the finished element off the mandrel. The sweep 150 preferably is in the form of an elongated arm the end of which bears against the mandrel and extends right angularly therefrom. The sweep may be actuated by any suitable means such as a piston and cylinder 162 as illustrated in FIG. 3.

Binding elements made according to the foregoing

mechanism may then be inserted in the drilled openings of a pad of paper either manually by spreading apart the legs sufficiently to insert them in the openings or an automatic mechanism may be provided to carry out this operation as suggested in FIGS. 4 and 5.

In the FIG. 4 device, the element 120 is held in position by an arm 159 that engages the cross-piece 122 while an offset member 161 pivots against the loops 124 to open and close them. In FIG. 5, the element is restrained by a slide pin 163 while a hook-like arm 165 pulls against the cross-piece 122 to open the loops. A spring loaded treadle and crank are employed to actuate the arm 165.

Having thus described the invention what we claim and desire to obtain by Letters Patent of the United States is:

1. Apparatus for forming a plastic binding element having a straight cross-piece and a plurality of circular loops from a starting element having a straight cross-piece and a plurality of straight legs extending perpendicularly therefrom, comprising

- (a) an inclined chute adapted to store a quantity of said starting elements,
- (b) heating means adjacent said chute for softening said elements,
- (c) feed means for releasing said elements one by one down said chute,
- (d) a die located at the end of said chute to receive each of said elements,
- (e) said die being formed with separable portions

formed with a cylindrical passage and a cylindrical member mounted therein,

5 (f) the walls of said passage being formed with a plurality of spaced arcuate grooves to receive the legs of said element and the surface of said member being formed with a longitudinal groove to receive said cross-piece,

(g) means to rotate said member when said cross-piece is received in said groove to wrap said legs about said member and form them into loops, and,

10 (h) means to separate said die portions and remove said element after said element has been set.

2. Apparatus according to claim 1 including another heat source prior to said first mentioned heat source for pre-heating said elements.

15 3. Apparatus according to claim 1 including cooling means connected to said die.
